TELEVISION TRANSMITTING TUBE

Harley A. Iams, Berkley Heights, N. J., assignor to
 Radio Corporation of America, a corporation of
 Delaware

Application June 24, 1939, Serial No. 280,999

9 Claims. (Cl. 250—150)

My invention relates to television transmitting tubes and is more particularly directed to tubes utilizing low velocity electron scanning beams and incorporating electron multiplier arrangements.

Television transmitting tubes of the low velocity electron beam scanning type have been made in which a combination magnetic-electrostatic deflection system including electrostatic plates wholly immersed in a uniform axial magnetic field shifts the beam in a plane parallel to the plates. Such tubes have not been satisfactory when made to incorporate electron multiplier elements because the electrons directed toward the target electrode return along dissimilar paths and are distributed over a long line or over an area substantially as large as the target. The electrons could not be collected over a relatively small area and the fullest advantage of electron multiplication could not be obtained. A further limitation to the amplification which can be given the signals from a television pick-up tube is the level of other disturbing signals or noises. In such an arrangement as above described the optimum ratio of picture to noise signal is not obtained when the initial amplification is obtained by means of an electron multiplier located within the pick-up tube because photo-emission from the target is multiplied along with the electrons representing the signal energy.

It is an object of my invention to provide a television transmitting tube of the low velocity electron beam scanning type wherein electron multiplication may be utilized to its fullest advantage. It is another object of my invention to provide such a tube wherein the electrons not reaching the target may be intercepted over a relatively small area outside of the region between the electron source and target for electron multiplication purposes. It is a further object to provide a low velocity electron beam scanning tube wherein energy representative of the desired signals may be separated from non-signal energy, and it is a still further object to provide a tube wherein the signal may be amplified by electron multiplier arrangements while keeping the noise distortion at a minimum value.

In accordance with my invention, an electrostatic image corresponding in electrostatic energy distribution to the light distribution of an optical image is formed on a target or mosaic electrode which is scanned with a low velocity electron beam from an electron source such as an electron gun, the scanning being accomplished in a combination magnetic-electrostatic field in

such a manner that a portion of the electrons directed toward the target electrode return toward the electron gun along dissimilar paths and over a relatively small area so that an electron multiplier in the path of the returning electrons receives no energy except that representative of the returning electrons which are modulated in intensity by the electrostatic image formed on the target. More particularly in accordance with my invention, I provide a structure which separates the electrons representative of signal energy from other electrons generated during the normal operation of the tube.

A better understanding of my invention will be obtained and other objects, features and advantages will appear from the following description taken in connection with the accompanying drawings in which:

Fig. 1 is a cross-sectional view of a television transmitting tube and circuit embodying my invention, Fig. 2 is an elevation perspective view of the tube shown in Fig. 1, Fig. 3 is a plan perspective view showing a modification of my invention, and Fig. 4 is likewise a plan perspective view of a tube incorporating another modification of my invention.

In general, the apparatus of my invention comprises an evacuated envelope having a target preferably of the photosensitive mosaic type at one end thereof and an electron gun and electron multiplier at or near the opposite end of the envelope. The target, if of the mosaic type, is provided on its front surface with an extremely large number of mutually insulated photoelectrically sensitized particles and is so positioned that it may be scanned by an electron beam from the gun and may also have focused upon it an optical image of the object of which a picture is to be transmitted. The electron gun is of a conventional type and is preferably displaced from the center line of the tube so that it will not be in the path of electrons returning from the target. The potential between the electron gun and target is so adjusted that the electron beam is projected at relatively low velocity and directed upon the target at extremely low or substantially zero velocity, that is, at a velocity approaching zero at the point of impact therewith. The electron multiplier is preferably offset from the center line between the electron gun and target and is arranged to receive the electrons which do not impinge on the target by reason of their low velocity. In operation elemental areas of the mosaic electrode acquire electrostatic potentials proportional to the in-

tensity of the light incident thereon, thus particles of the mosaic which are more highly illuminated acquire the more positive electrostatic charges with respect to the unilluminated particles, and these positive charges which represent an electrostatic image of a picture to be transmitted are neutralized by a portion of the low velocity electrons in the scanning beam, the remaining electrons being reflected from the target. Intermediate and extending wholly between the electron gun and the electron multiplier with respect to the target, I provide a uniform axial magnetic field and means within the field to generate an electrostatic field to scan the electron beam from the gun over the target and cause the electrons returning from the target to be directed over dissimilar paths to the relatively small area occupied by the electron multiplier. Since the electron gun and electron multiplier are offset one from the other, the advantages of such an arrangement to be hereinafter described, means are provided for lifting the electron beam from one path to another path which is parallel with the first path so that the beam may be scanned over the target and a portion returned along dissimilar paths to the relatively small area occupied by the electron multiplier.

Referring particularly to my tube structure as shown in Figs. 1 and 2, the tube includes an elongated evacuated envelope enclosing at one end a target or mosaic electrode 2 and at the opposite end, an electron gun assembly 3 adapted to project electrons toward the mosaic electrode and, at the same end as the electron gun opposite the mosaic electrode 2, an electron multiplier 4 offset from the electron gun in a direction transverse to a direct line between the electron gun and the mosaic electrode.

The mosaic electrode 2 which faces the electron gun preferably comprises a substantially transparent sheet of insulation such as the mica sheet 5, having on its rear surface a translucent or semitransparent electrically conducting film 6, the front surface of the mica sheet being provided with an exceedingly great number of mutually separated photosensitive particles 7. In making the mosaic electrode I select a mica sheet 5 of the desired area and having a uniform thickness of approximately .002 inch, and as a first step coat one side of the sheet with an electrically conducting film of metal of sufficient thinness as to be substantially transparent so that an optical image such as represented by the arrow 8 may be focused on the photosensitive particles 7 by the lens system 9. The mosaic of mutually separated particles may be made in a number of ways well known in the art such as by depositing on the sheet of mica finely divided silver oxide which is reduced by suitable heat treatment and formed into the mutually separated and insulated particles 7 following which the particles may be oxidized and sensitized with caesium or other alkali metal during the evacuation of the tube. Such an electrode structure and a method of sensitization is disclosed by S. F. Essig in U. S. Patents 2,020,305 and 2,065,570.

The electron gun assembly 3 is of a conventional type and comprises a cathode 10 from which electrons may be drawn, a control electrode 11 connected to the usual biasing battery, and a first anode 12 maintained positive with respect to the cathode 10. The electron stream leaving the first anode 12 is accelerated at relatively low velocity and concentrated into an electron scan-

ning beam focused on the front surface of the target or mosaic electrode by the axial magnetic field and the electrostatic field from a second anode 13 which is preferably an apertured tubular member partially surrounding the first anode 12. The first anode 12 and the second anode 13 are maintained at the desired positive potential with respect to the cathode by a battery 14. The cathode 10 is preferably connected directly to the electrically conducting film 6 of the mosaic electrode so that this conducting film may be maintained at cathode potential, although the conducting film 6 may be maintained slightly positive or negative with respect to the cathode.

In accordance with my invention the electron multiplier 4 is located near the electron gun, that is, oppositely disposed from the mosaic electrode 2 and out of the path of the beam projected from the electron gun to the mosaic electrode for all positions of the scanned beam. The electron multiplier is thus offset from the electron gun structure while, at the same time in accordance with my invention, it is capable of receiving electrons directed by the electron gun toward, but not reaching the mosaic electrode.

The electron multiplier 4 may follow one of the well-known designs, such as a structure which comprises any desired number of perforated electrodes such as the wire mesh screens 15, 16, 17 and 18 interposed in the order named between the mosaic electrode and an electron collecting electrode or anode 19. These wire mesh screens are constructed of bright nickel or of other material having good secondary electron emitting properties. For ease in assembly I prefer to support the wire mesh screens by concentric metallic cylinders 20, 21, 22 and 23 which are in electrical contact with their respective wire mesh screens and connected to a potential source such as the battery 24 through a bleeder resistance 25, the wire screen 15 and its associated supporting cylinder being connected to ground and consequently to the anode 13. The electron collecting electrode or anode 19 serves as an output electrode for the tube and is connected through an output impedance 26 to an input electrode of a translating device 26' and to the positive terminal of the battery 24 so that signals generated in the tube may be amplified and applied to a transmission network as well known in the art.

In accordance with my invention I provide intermediate the electron gun and the target or mosaic electrode means to deflect the beam and further means to raise the beam so that it impinges on or is directed toward points of the mosaic electrode outside of the direct line between the gun and mosaic electrode, the latter means simultaneously serving to raise the electrons of the beam not reaching the target to a plane parallel to the plane in which the electrons are deflected so that they may be directed toward the electron multiplier over paths dissimilar from those along which they approach the mosaic electrode. In addition, I provide further deflection means to absorb the deflection produced by the first deflection means, that is, to deflect the beam in the opposite direction and by an amount equivalent to the first deflection and in a plane parallel with the plane of the first deflection. This deflection, however, is in an opposite direction than that afforded by the first deflection so that the returning electrons may be directed to a point offset from their point of origin in the electron gun at which point is located the electron multiplier 4. To provide proper functioning

of the beam deflection means, I provide a magnetic coil 27 which completely surrounds the envelope 1 to generate a magnetic field having lines of force parallel with the center lines between the 5 multiplier and electron gun to the target. This field extends over and preferably beyond the space separating the electron gun and electron multiplying structure from the mosaic electrode.

More particularly, and again referring to Figs. 10 1 and 2, I provide deflection plates 28-29 positioned 15 between the electron gun and the mosaic electrode, one on either side of the direct path between said electron gun and mosaic electrode. Another deflection plate 30 coextensive with and 20 parallel to the plate 29 is located on the side of the plate 29 opposite the plate 28 so that the plates 29-30 are on opposite sides of the direct path between the multiplying structure 4 and the mosaic electrode 2. The plates 28 and 30 are connected together and with the plate 29 are connected to a source of deflection potential and to ground through a center-tapped resistance 31 which may be of the order of 1 to 10 megohms. The deflection plates 28-29 are wholly immersed 25 in the magnetic field generated by the coil 27. As the electrons from the electron gun pass into the combination magnetic-electrostatic field between the plates 28-29, the electrons are deflected in a plane parallel with the plates and follow a path such as represented by the dashed line 32.

Further in accordance with my invention, I provide in the space separating the plates 28, 35 29 and 30 from the mosaic electrode 2, a pair 30 of "lifter plates" 33-34 which are widely separated transverse to the tube axis and located in planes substantially perpendicular to the plates 28-30 and to the plane of deflection between the plates 28-29. As the beam passes from the 40 deflection plates 28-29, it passes along parallel paths by reason of the axial magnetic field, such a path being represented by the line 35, and into the field of the lifter plates 33-34, whereupon the beam follows a path 36 which is inclined at 45 an angle to the plane of deflection between the plates 28-29. After the beam leaves the field between the plates 33-34, it approaches the mosaic electrode 2 along parallel paths by reason of the axial magnetic field and by reason of the 50 deflection potentials applied to the plates 28-29, which beam may be made to trace a single line of elemental beam width over the mosaic electrode. It will be observed that the lifter plates 33-34 perform a double function, namely, to lift 55 the beam to a plane parallel with the plane of deflection and through the tube axis such as a plane through the plate 29 and to further lift the electrons reflected from the mosaic electrode to a plane parallel with and substantially mid-way between the plates 29-30. It will be obvious 60 that both plane surfaces of the plate 29 are utilized to produce, in combination with the adjacent surface of the plate 28 and of the plate 30, electrostatic fields which are utilized in the 65 operation of the device. I may therefore choose to use two closely spaced or contiguous plates in place of the single plate 29. Thus the plates 28-29 may be referred to as means to deflect the beam in a unidirectional manner and the 70 plates 29-30 as means to absorb the deflection imparted to the electrons by the plates 28-29. In order to obtain scanning in a direction normal to the scanning produced by the plates 28-29, I provide between the lifter plates and 75 the mosaic electrode a pair of magnetic deflection

coils 38-39 so that the beam may be scanned over any desired area of the mosaic electrode.

During operation the light or image such as represented by the arrow 8 projected on the mosaic electrode liberates photoelectrons from the particles 7 in proportion to the light intensity on the individual particles, and since the electrically conducting film 6 is operated at or near cathode potential, the electrons approaching the mosaic electrode such as along the path 10 37 are decelerated and proceed toward the mosaic electrode with a velocity approaching zero. The electrons directed toward the particles 7 which are positive with respect to the cathode will be collected by the particles, whereas electrons approaching unilluminated particles on the mosaic will be reflected from the mosaic along paths such as represented by the line 40, which are initially substantially coincident with the paths of approach to the target. Since the plates 28-30 have a mean ground potential, the electrons are drawn from the mosaic electrode with increasing velocity as they leave the vicinity of the mosaic electrode and are drawn into the field between the lifter plates 33-34, whereupon the returning electrons are lifted by an amount equivalent to that by which they were lifted over the path 36 to a new path such as represented by the line 41. The electrons then follow substantially parallel paths, one such as 30 represented by the line 42 in a plane parallel with the plates 29-30 and midway therebetween. Since the electrons are moving in a direction opposite to that followed while moving toward the mosaic electrode and since the plates 28 35 and 30 are interconnected and supplied with deflection potential with respect to the plate 29, the returning electrons are deflected along a path 43 by an amount equal to the deflection along the path 32 and are directed into the electron 40 multiplier 4. Those electrons which impinge upon the wire mesh screen 15 of the multiplier 4 release a great number of secondary electrons 45 which are drawn toward the wire mesh screen 16 where the energy is similarly multiplied since the electrons are subjected to a higher potential field generated by the battery 24 and impinge on the wires of the screen 16. Similar electron multiplication takes place from the wire mesh screen 17 and 18, whereupon the electrons are 50 collected by the anode 19 for utilization purposes. While I have disclosed the use of a four-stage electron multiplier, it is obvious that a multiplier having any desired number of stages may be used, and I do not wish to be limited to 55 the particular structure shown.

Since the plane of deflection between the plates 28-29 and the plane of deflection between the plates 29-30 are parallel and equidistant, the space being determined by the distance the electron gun is offset from the electron multiplier, the amount of lifting imparted to the beam between the plates 33-34 along the path 36 is equivalent to the lifting of the beam along the path 41, and consequently, I desire to maintain 60 a uniform potential gradient between the plates 33-34 so that the amount of lifting will be the same for all potentials applied between the deflection plates 28-29. The plates 33-34 are therefore connected through a center-tapped 65 bleeder resistor 44 to a potential source such as the battery 45. While I have shown the polarity of the battery 45, reversal of the magnetic field generated by the coil 27 will necessitate reversal of this polarity. It is also desirable that the 70 75

electron beam pass between the lifter plates in a region of constant potential even though the beam is deflected horizontally by the deflection plates. I therefore prefer to apply a small amount of the horizontal deflection potential across the lifter plates 33-34 so that the beam while passing between the lifter plates passes through a zero potential gradient with respect to ground. To accomplish this mode of operation I connect the center tap of the bleeder resistor 44 to a point on the resistance 34 close to the grounded center tap of this latter resistance. While I have shown this connection as being made to the left of the grounded center tap of the resistor 34, the connection is made to the opposite side of the center tap if the direction of the axial magnetic field produced by the coil 27 is reversed. While I prefer to locate the electron gun in the region of the electron multiplying structure as shown in Figs. 1 and 2, the arrangement wherein the electron gun and multiplier are offset along the axial magnetic field as shown in Fig. 3 offers certain advantages. Referring to Fig. 3 wherein the electrode structure corresponding to that shown in Fig. 1 is similarly referenced, the electron gun 3 is located in an offset manner from the center line of the tube and offset from the deflection plates 50-51. In this construction I provide lifter plates 52-53 connected to a source of D. C. potential between the electron gun and the deflection plates 50-51. In operation the electron beam from the gun is directed toward the mosaic electrode 2 and into the field between the lifter plates 52-53, whereupon the beam is lifted such as along the path 54 into a plane substantially midway between the deflection plates 50-51, whereupon the beam is deflected in a plane parallel with the plates along the path 55 and subsequently along a path 56 toward the mosaic electrode. For purposes of clarity I have not shown the coil 27 used to generate the axial magnetic field nor the coils 38-39 used to deflect the beam in a direction perpendicular to the direction produced by the plates 50-51. The electrons not reaching the mosaic electrode return along paths such as represented by 57 substantially coincident with that represented by 56 and enter the deflection field between the plates 50-51, whereupon they are deflected by an amount equal to the deflection along the path 55 as shown at 58. It will be evident that the beam suffers no further deflection after it leaves the field between the plates 50-51 along the path 56, so that for maximum deflection of the beam across the mosaic electrode, that is, in a horizontal direction, the plates 50-51 should be at least as wide as the mosaic electrode, both of these directions being in the plane of the plates and normal to the tube axis. Since, however, the deflection of the electrons returning from the mosaic electrode along the path 58 is equivalent to and in the same direction as the deflection along the path 55, the deflection plates must be at least twice as wide as the effective width of the mosaic electrode.

In accordance with the modification of my invention shown in Fig. 3 I provide means such as a further set of deflection plates 59-60 on the opposite side of the deflection plates 50-51 from the mosaic electrode 2 to absorb the deflection imparted by the plates 50-51 to the electrons of the beam which are unabsorbed by the mosaic electrode. The plates 59-60 are preferably in the same planes as the correspondingly positioned

plates 50-51. The two sets of deflection plates are interconnected so that the plate 50 is tied to the plate 60 and the plate 51 to the plate 59, the source of horizontal deflection potential being applied to the two sets of plates as shown in Fig. 3. After the returning electrons pass along the path 53, they leave the deflection field between the plates 50-51 and follow parallel paths into the reverse field between the plates 59-60, whereupon the electrons are deflected in a plane parallel with the plane of deflection between the plates 50-51 along a path such as the path 61 to the electron multiplier 4 where the energy representative of these electrons is multiplied, collected and fed to an amplifying arrangement as shown in Fig. 1. Since the deflection between the plates 59-51 along the paths 55 and 58 is cumulative, the deflection plates 59-60 should likewise be at least twice as wide as the mosaic electrode or as wide as the deflection plates 50-51 and should have a length twice the length of the plates 50-51, since the lateral displacement of the electrons along the path 61 is equivalent to the combined displacement along the paths 55 and 58. Another modification of a television transmitting tube made in accordance with my invention is shown in Fig. 4 wherein the electron gun 3 and the electron multiplying structure are similarly positioned as shown in Fig. 3. Electrode structure similar to that shown in Figs. 1, 2 and 3 is similarly referenced and I have again omitted showing the magnetic coil 27 and the vertical deflection coils 38-39 for purposes of simplicity. The path of the beam as it leaves the electron gun passes through the lifter plates 52-53, the deflection plates 50-51, and a portion of the beam returns through the deflection plates 50-51 along paths similar to those shown in Fig. 3. After the returning electrons leave the field of the plates 50-51, they are directed along parallel paths in the plane of deflection produced by the plates 50-51 toward the electron multiplier 4 which is located along the tube axis and in the plane of deflection. Between the electron gun 3 and the multiplier 4 I provide means such as a system of deflection plates immersed in the magnetic field generated by the coil 27 to absorb the deflection energy imparted by the plates 50-51 to the electrons of the beam which are unabsorbed by the mosaic electrode. This system of plates comprises the cross-connected plates 62-63 and the cross-connected plates 64-65. The two pairs of cross-connected plates are connected to a suitable source of D. C. potential. While I have shown the polarity of the D. C. potential applied to the two pairs of cross-connected plates, the polarity should be reversed for a reversal of the field developed by the coil 27.

In operation of the tube shown in Fig. 4, the electrons returning from the deflection plates 50-51 such as along the path 66 enter the deflection field between the plates 63-65, and since these plates are cross connected and the polarity of the D. C. voltage is suitably chosen, the returning electrons are directed toward the tube axis. At the time or shortly before the electrons reach the tube axis they leave the deflection field between the plates 63-65 and are controlled solely by the axial magnetic field, whereupon they travel parallel with and along or close to the tube axis and are collected by the electron multiplier. If, however, the deflection is on the opposite side of the tube axis from that shown in the drawings, the plates 62-64 will direct the returning electrons toward the tube axis, whereupon at the time

or shortly before the electrons reach the axis they are controlled solely by the magnetic field and proceed to the electron multiplier.

While I do not wish to be limited to the particular theory which I have evolved to explain the improved operation of my device, it seems probable that the electrons which are directed toward the mosaic electrode are modulated in accordance with the electrostatic energy distribution produced on the mosaic electrode in accordance with the light and shade of the optical image. The electrons returning from the mosaic electrode are directed along definitely controlled paths differing from the paths along which the electron beam approached the mosaic over the major length of the tube and are collected over the relatively small area occupied by the electron multiplying structure. In this way it is possible to collect all of the returning electrons so that electron multiplication may be effected. The photo-electrons liberated by the mosaic electrode under the influence of light are accelerated toward the electron multiplier, but substantially all of these photo-electrons are collected either by the deflection plates or by a grounded conductive wall coating (not shown) in the region of the mosaic electrode which may extend over the entire length of the tube. Very few of the photo-electrons return to the multiplier because the combined magnetic-electrostatic fields lift and deflect these electrons from the paths to the electron multiplier. Thus while a few photo-electrons under conditions of zero deflection may be intercepted by the electron multiplier, it is impossible for the large majority of these photo-electrons to be collected on the output electrode nor is it possible for them to enter the multiplier where their energy might be amplified and produce distortion of an appreciable amount.

40 I claim:

1. A television transmitting tube comprising an elongated envelope, a target electrode adjacent one end of the envelope adapted to have an optical image focused thereon, a system of electrostatic field generating plates between said target and the opposite end of said envelope from said target, said system of plates including a central and two outer plates spaced apart in a direction normal to the longitudinal axis of said tube, an electron gun adjacent the edges of the central and outer plate of said plates opposite from said target to develop and direct a beam of electrons between said central and outer plates, an electron collecting electrode positioned adjacent the edges of the central plate and the remaining outer plate opposite from said target to receive electrons from said gun not reaching said target, means to generate a magnetic field having lines of force extending from said electron gun and collecting electrode to said target, and a pair of plates intermediate the said system of plates and said target for, in combination with said field, deflecting said beam and the electrons returning from said target in a direction normal to the original direction of deflection of the beam produced by said central plate and said one outer plate and to the direction of said returning electrons within said central plate and the said remaining outer plate.

70 2. A television transmitting tube comprising an elongated envelope, an electron gun and a target electrode adjacent opposite ends of said envelope, a magnetic focusing coil surrounding said envelope to generate a magnetic field having lines of force parallel with the center line

between said gun and target, means comprising a first pair of deflection plates each plate of said pair being positioned on either side of the path between said gun and target to deflect the beam over said target in a direction parallel with said plates, a pair of plates substantially perpendicular to the planes of said first pair of plates to lift the beam of electrons to a plane parallel with and displaced from the plane of deflection between said first pair of plates and to additionally lift the electrons of the beam not reaching said target to another plane parallel with and displaced from the plane of deflection between said first pair of plates, means including one of the plates of said first pair to deflect the electrons of the beam not reaching the target in an opposite direction than the deflection imparted by the said first pair of plates to the electrons of the beam, and electron collecting means removed from the path between said gun and target to collect the electrons returning from said target.

3. A television transmitting tube comprising an elongated envelope, a target electrode, means to project an optical image on said target electrode, an electron gun oppositely disposed from said target electrode to generate and direct a beam of electrons toward said target, means to generate a magnetic field having lines of force substantially parallel to the undeflected path of said beam, a pair of spaced parallel plates, one on either side of the path of said beam to deflect the beam in a plane parallel with the plates, means to deflect the electron beam from the plane of deflection between said plates to a plane substantially parallel therewith and to deflect electrons not reaching said target to another plane parallel with said first-mentioned plane of deflection, means including one of said plates to deflect the electrons, which return from said target, in a direction opposite from that produced by said first pair of plates and means in the path of said returning electrons to electronically multiply the returning electrons to generate electrical currents representative of elemental areas of said optical image.

4. A television transmitting tube comprising an elongated envelope, a target electrode adapted to have an optical image focused thereon from a point outside said envelope, an electron gun offset from the longitudinal axis of said tube to generate an electron beam, means in the path of said beam to displace said beam to a path substantially coincident with said longitudinal axis, means including a pair of deflection plates to deflect the beam in a plane parallel with the planes of the plates, means more removed from said target than said electron gun to deflect the electrons of the beam not reaching the target, in a direction opposite to the deflection imparted by said pair of plates to the electrons reaching said target, means to intercept the electrons returning from said target after the deflection produced by said last mentioned means and means to generate a magnetic field having lines of force extending substantially normal to said target and extending from said target to said electron intercepting means.

5. A television transmitting tube comprising an electron gun to develop a beam of electrons, an oppositely disposed target electrode adapted to have an optical image focused thereon and to be scanned with the electron beam from said gun, means to generate a magnetic field having lines of force parallel with the center line between and intercepting said gun and target,

means including a pair of oppositely disposed plates, one on either side of a portion of the path of the electron beam between said gun and target to scan said beam over said target, a collecting electrode to collect electrons of the beam not reaching said target wholly removed from the path of said beam when scanned over said target by said plates, and a second pair of plates wholly immersed in said magnetic field to direct the electrons not reaching said target to said collecting electrode.

6. A device for generating television signals comprising an evacuated envelope having a window, a target including a mosaic of mutually separated photosensitive particles positioned to have an optical image formed thereon through said window, an electron gun in said envelope oppositely disposed from said window and said target to generate and direct an electron beam toward said target, magnetic means to constrain the electron beam and direct it along a path normal to said target, a pair of oppositely disposed electrostatic deflection plates associated with said last-named means to deflect the beam from the said path in a plane parallel with said plates, means to displace the deflected beam into a plane parallel with but spaced from said first-mentioned plane to scan said target, means to deflect the electrons not reaching said target in a direction opposite to the deflection produced by said first-mentioned deflection to a point outside of the paths followed by said beam from said gun to said target to return said electrons over a relatively small area, and electron collecting means across the path of the electrons returning from said target.

7. A television transmitter comprising an evacuated envelope having a window therein, an electron emissive light sensitive target positioned to receive an optical image through said window, an electron gun positioned within said envelope to develop and project an electron beam toward said target with a velocity approaching zero in the vicinity of said target, means to generate a magnetic field having lines of force normal to said target and extending at least between said gun and target, a pair of electrostatic deflection plates wholly immersed in said field one of said plates being on each side of a portion of the beam path to deflect and scan the beam over said target, means comprising a second pair of plates wholly immersed in said field and over another portion of the beam path to prevent electrons not reaching said first-mentioned target from returning along the paths followed by the beam between said deflection plates and means wholly removed from the paths followed by the

beam during scansion of said target, to collect the electrons not reaching said target.

8. A device for generating television signals comprising an elongated envelope having a window, a target including a mosaic of mutually separated photosensitive particles exposed to said window to have an optical image formed thereon through said window, means surrounding said envelope to generate a magnetic field having lines of force substantially perpendicular to said target, means outside of a path normal to and intercepting said target to generate an electron beam, means along the path of the beam and wholly immersed in said field to displace the beam into a position directed toward said target, deflection means including a pair of oppositely separated plates wholly immersed in said field to deflect the beam in one direction over said target, means to deflect the beam in a direction substantially normal to the deflection produced by said pair of plates, a system of deflection plates more remote from said target than said beam generating means to deflect the electrons of the beam not reaching said target, in a direction opposite to the deflection imparted by said first deflection means and means more remote from said target than said gun and said system of plates to collect the electrons not reaching said target.

9. A television transmitting tube comprising an elongated evacuated envelope enclosing a target having mutually separated photosensitive particles adapted to have an optical image focused thereon, an electron gun displaced from the longitudinal axis of said envelope to generate and project an electron beam in the direction of said target, an electron focusing coil surrounding said envelope to generate a substantially uniform magnetic field having lines of force parallel with said longitudinal axis, means to deflect the beam of electrons at a substantially constant angle toward said longitudinal axis, a pair of deflection plates, each of which are positioned on opposite sides of the said axis to deflect the beam over said target and to deflect electrons not reaching said target from the paths followed by said beam while passing through said plates, two pairs of plates more removed from said target than said gun, each pair of said plates lying in a plane parallel with said first-mentioned deflection plates and on opposite sides of said axis, the plates of one pair being oppositely disposed from the plates of the other pair to return the electrons not reaching said target to the said axis and means along the axis of the tube to collect the returning electrons.

HARLEY A. IAMS.

CERTIFICATE OF CORRECTION.

Patent No. 2,213,177.

August 27, 1940.

HARLEY A. IAMS.

It is hereby certified that error appears in the printed specification of the above numbered patent requiring correction as follows: Page 6, first column, line 48, claim 7, after the word "field" insert a comma; line 54, same claim, strike out "first-mentioned" and insert the same before "deflection" in line 56, same claim; and that the said Letters Patent should be read with this correction therein that the same may conform to the record of the case in the Patent Office.

Signed and sealed this 11th day of February, A. D. 1941.

(Seal)

Henry Van Arsdale,
Acting Commissioner of Patents.
